ATTORNEY

UNITED STATES PATENT OFFICE

ALBERT W. BENNETT, OF NEWARK, OHIO

COLLAPSIBLE SHOE LAST

Application filed April 4, 1929. Serial No. 352,498.

This invention relates to lasts upon which shoes are manufactured and is more particularly concerned with a sectional last having a section lock joint effective to hold the last sections fixed in their fully extended shoe making position but breakable to decrease the overall length of the last and permit the removal of the last from the finished shoe without damage thereto.

10 In the manufacture of shoes from one piece lasts, many shoes are damaged by the forcible pulling of a solid one-piece last from the finished shoe at the end of the manufacturing cycle and the last of the present invention is especially advantageous in that this large item of loss in manufacture may be avoided by its use.

In accordance with the present invention, the last is formed in two sections having connection at the forward end of the heel section, these sections being jointed for full length locked distention for the assembly and manufacture of the shoe thereon, the section lock joint being thereafter breakable and the sections cooperating therewith to permit movement of the heel end of the last upwardly and forwardly of the shoe in the normal pulling direction of the heel end of the last to decrease the overall length of the last in the shoe and permit the bodily extraction of the broken last sections without imposing damaging strain on the shoe parts.

The invention consists in the construction, arrangement and combination of parts as hereinafter more fully pointed out and claimed, and in a preferable form, is illustrated in the accompanying drawings forming part hereof, and in which:

40 Figure 1 is a longitudinal sectional view of a last constructed in accordance with the present invention.

Figure 2 is a transverse horizontal section through the last section lock joint, taken on the line 2-2 of Figure 1.

45 Figure 3 is a detail perspective view of the mortise plate of a dove tailed section connection, in the inverted position of Figure 1, this plate being applied to the rear end of the fore-part of the last.

50 Figure 4 is a similar perspective view of

the cooperating wedging tenon plate of the dove tailed section connection applied to the heel section of the last.

Figure 5 is a detailed perspective view of the link joining the mortise and tenon plates, 55 detached, with spring omitted to disclose the mounting of the spring tensioning abutment pin in the link.

Referring to the drawings by numerals, it will be seen that the last comprises a fore-part section 1 and a heel section 2, which may and preferably are of metal for durability, although obviously they may be made from wood in accordance with present day practice. The upper portion of the heel section is cut back at 3 providing a space 4 in the fully distended operative positions of the last sections shown in Figure 1 providing for diagonally upward and forward movement of the heel section toward the fore-part section when the connection lock is broken and the heel section moved upwardly and forwardly toward the toe to decrease the overall length of the last for extraction from the shoe.

The lower portions of the abutting end faces of the forepart and heel sections have downwardly and rearwardly inclined faces 5 which abut in the fully distended locked operating positions of the last sections. Preferably, these faces are formed with cooperating stop shoulders 6 engaging and positioning the bottom of the sections with their sole and heel faces in alignment in the operative position of the sections as shown in Figure 1. The sole of the fore-part adjacent to and along 80 its edge may be grooved as shown at 7 in Figure 1 to provide a strip to receive lasting tacks.

Below its upper face, the rear end of the fore-part is formed with a forwardly extending socket 8 open at its rear end with its bounding rear edges extending from adjacent the upper face of the last section downwardly and rearwardly with successive inclines 9 and 10 of successively decreasing 95 angularity to the vertical so that adjacent the sole line of the last the angularity more nearly approaches the vertical. The rear face of the fore-part above the socket 8 is formed with an overhang 11. The face of 100

the rear end of the fore-part around and outlining the edge of the socket 8 is shou-
dered to provide an abutment ledge 12 ex-
tending around and edging the socket with
the face of the ledge inclined and extending
in parallel to the inclines or bevels 9 and 10.
That portion of the fore-part 1 adjacent to
the ledge 12 is also an overhang, the sliding
motion of the heel part 2 being limited by
these overhangs.

10 The heel section 2 is provided with the
usual jack pin socket with the lower end of
the socket, in the distended position of the
sections in Figure 1, alined with the lower
end of recess 8 and counter-bored in aline-
ment therewith to provide a longitudinal slot
14 extending through its inclined face 5 to re-
ceive the link hereinafter described. This
slot is traversed adjacent to its rear end by a
bore 15 (Figure 2) for a link anchoring pin.

20 Seated with its edges resting on the abu-
ment ledge 12 of the fore-part section is what
may be termed the mortise plate of a wedg-
ing dove-tailed connection for the two last
sections, this plate being detailed in Figure
25 3 and generically designated 16.

This mortise plate 16 is formed with an
upper inclined portion 17 whose inclination
conforms to the inclined portion 9 of the
30 ledge 12 and with a lower inclined portion
18 of a different angularity conforming to
the inclined portion 10 of the ledge 12. This
plate, laterally, its tapered outwardly from
35 its upper edge downwardly to its junction
with the inclined portion 18 in conformation
with the usual cross sectional contour of a
last at this point and the inclined portion 18
may have side marginal edges 19 of reduced
40 thickness and edged inwardly at both sides
by flat ribs 20 extending from top to bottom
of the plate and having their confronting
edges 21 undercut as best shown in Figure 2.

The confronting undercut edges of these
45 ribs from the upper end of the plate down-
wardly to the junction midway thereof of
the relatively inclined portions 17 and 18,
extend in maximum spaced parallel relation.
From the point of this angular junction, these
50 confronting edges converge wedgingly, pre-
ferably, as shown in Figure 3, in two steps 22
and 23 of successively increasing convergence
with a stop shoulder 24 at their junction. Be-
tween these confronting edges the plate is
55 pierced longitudinally by an elongated slot
25. At the outer edges of the ribs 20 the plate
is formed with tapered bores 26 partly cut-
ting the outer side edges of the ribs 20 to re-
ceive and countersink the heads of screws by
means of which the plate 16 is secured to the
60 ledge 12.

The inclined portion 5 of the front face of
the heel section edging the slot 14 there-
through is channelled to provide an abu-
ment ledge 27 edging said channel and form-
65 ing a seat for the outer edges of a dove-tail-

ing tenon wedge plate shown in detail in
Figure 4 and generically designated by 28.
This plate 28 is substantially rectangular in
outline and is provided with a tenon 29 offset
from its face centrally thereof and having
70 undercut edges corresponding to the under-
cut edges 21 of the ribs 20 of the mortise plate,
the tenon having its sides provided with suc-
cessive wedging tapers 30 and 31 correspond-
ing to the space separating the confronting
75 tapered side edges 22 and 23 of the mortise
plate ribs wedgingly to interfit therebetween,
these tapers 30 and 31 being joined by shoul-
ders 32 designed to abut the shoulders 24 of
the mortise plate ribs 20 when the tenon 29
80 is wedgingly seated between the tapered por-
tions 22-23 of these ribs. The tenon plate 28
at the opposite sides of its tenon is pro-
vided with a series of holes 33 drilled there-
85 through to receive screws 34 for attaching
the sides of the plate to the ledge 27 of the
heel section. The plate 28 is also pierced
centrally and longitudinally of the tenon by
an elongated slot 35 alining with the slot 14
90 of the heel section 2 in the attached position
of the plate and with the slot 25 of the mor-
tise plate and the socket 8 of the fore-part
section 1.

A link in the form of a flat bar 36, shown
in detail in Figure 5, extends through the
alined slots 25, 35 of the mortise and tenon
plates 20, 28, its rear end projecting into
the slot 14 of the heel section and having a
bore 37 through which extends a pin 38 driven
95 through a transverse bore in the heel section,
this pin being held in said bore by any suit-
able means after insertion, such for example
as upsetting its ends. The rear end of the
link is therefore anchored to the heel section
100 by said pin.

The forward end of the link bar 36 ex-
tends forwardly through and beyond the mor-
tise plate slot 25 for a substantial distance.
This forwardly projecting portion is formed
110 with a longitudinal slot terminating short of
the forward end of the bar and having an en-
trance lateral extension 39 at its forward end
of at least coincident width. At its forward
end it is traversed by a fixed cross pin 40, the
projecting ends of which constitute a spring
115 abutment. A sliding abutment pin 41 is
formed with an intermediate diameter sub-
stantially coincident with the width of slot
38 and a length permitting the insertion of
this portion through the entrance lateral 39
120 into slot 38. The ends of pin 41 project lat-
erally from the opposite side faces of the bar
link 36 and are of increased diameter to re-
tain the pin against transverse displacement
from the slot 38, and provide laterally offset
abutments engaging the inner face of the
mortise plate 16 at opposite sides of the slot
25 therein and yielding held against said
125 plate by the tension of a coiled spring 42

encircling the bar link 66 between the fixed and movable pin abutments 40 and 41.

The tension of spring 42 acting against the fixed abutments 40 is transmitted by the 5 bar link 36 to the anchoring pin 38 of the heel section and urges the inclined face of said heel section against the corresponding inclined abutting face of the fore-part section. In the distended operating position 10 of the last sections shown in Figure 1, the spring exerts its tension to hold the heel sections locked together. In this distended position of the sections, the wedging tenon 35 of the tenon plate is seated in the wedging groove of the mortise plate between successive wedging tapers 22-23 and is wedged downwardly therebetween. The tension of the coiled spring 42 in this position, because 15 of the inclined face of the mortise plate against which its abutment pin 41 is held, holds the edge of the bar link tensioned against the mortise and tenon plates at the ends of their slots in a direction to increase the wedging interlock of said plates in the 20 distended operative position of the last sections shown in Figure 1.

To break this wedging interlock and reduce the overall length of the last sections for removal of the last from a shoe, a suitable tool having a pin insertible in the jack pin hole 13 of the heel section to grip said section, is used and by upward and forward pull thereon, the dove-tailing tenon plate is slid upwardly (or in the inverted position of 35 the last in Figure 1, downwardly) and forwardly over the forwardly inclined portion of the wedging groove between the ribs 20 of the mortise plate, with the tension of the spring 42 holding the tenon in the groove.

40 It is to be noted that with the wedging dovetail interlock of the last section junction plates and the support afforded by the jack whose pin engages in the jack pin hole 13 during pressure operations in the shoe making cycle, downward pressure on the fore-part of the last, as in sole leveling operations, tends to increase the wedging interlock of the junction plates, and downward pressure on the heel section of the last is 45 taken directly by the jack.

50 It will be evident that in the assembly of the parts, the mortise and tenon plates and their joint maintaining spring link will be assembled and the tenon plate first secured to the heel section of the last, after which the mortise plate is attached to the fore-part section, the tenon 29 being held in the groove of the mortise plate between the ribs 20 by 55 the tension of the coiled spring 42 of the connecting link bar. It will be evident also that in the reduction of the over all length of the last sections in the pulling of the last from a shoe made thereon, the heel section 60 of the last may be held stationary, as on a 65

jack pin, and the forepart of the last and the shoe moved relatively thereto.

The specific construction disclosed, while representing a preferred form of the invention, is intended as illustrative rather than restrictive thereof and structural variation and modification are contemplated in consonance with the spirit of the invention and the scope of the appended claims.

What I claim, therefore, and desire to 70 secure by Letters Patent is:

1. A sectional shoe last comprising a fore 75 part section and a heel part section divided along a line adjacent the front end of the heel portion of the last body, the rear face

80 of the fore part section having successive upwardly and forwardly inclined bevels from its sole edge upwardly joined at an angle intermediate the top and sole line of the fore part section and terminating below and under cutting the top face of said section

85 with the upper section of face bevel having a substantially increased component of forward inclination, the abutting front face of the heel section having its upper portion cut back from the confronting upper face of the fore part section from the angular junction of its face bevels upwardly and having the lower portion of its face beveled in correspond- 90

95 ence with the lower beveled face of the fore part section, and means joining and holding the beveled lower face of the heel section slidingly interlocked with the beveled lower and upper face of the fore part section for bodily sliding movement of the heel part section thereon along the line of said bevels

100 from a normal operative full last length position of the sections with their sole faces alined to an upwardly and forwardly moved position of the heel section with its lower beveled face engaging the upper portion of the confronting beveled face of the fore part section, said means joining the sections being 105 formed to interlock the sections rigidly together in said normal operative full last length position of the sections.

2. A sectional shoe last comprising a fore 110 part section and a heel part section divided along a line adjacent the front end of the heel portion of the last body, the rear face of the fore part section having successive upwardly and forwardly inclined bevels from its sole edge upwardly joined at an angle intermediate the top and sole line of the fore part section and terminating below and under cutting the top face of said section

115 with the upper section of face bevel having a substantially increased component of forward inclination, the abutting front face of the heel section having its upper portion cut back from the confronting upper face of the fore part section from the angular junction of its face bevels upwardly and having the lower portion of its face beveled in correspond- 120

125 ence with the lower beveled face of the fore part section.

65 70 75 80 85 90 95 100 105 110 115 120 125 130

fore part section, a mortise plate shaped to fit and secured to the upper and lower beveled face portions of the fore part section, a tenon plate shaped to fit and secured to the lower bevelled face of the heel section, and means holding said mortise and tenon plates in engagement for bodily sliding movement of the tenon plate and heel section from a normal shoe holding full last length position 10 with its tenon plate seating on the lower beveled portion of the fore part mortise plate and its sole face alined with that of the fore part section, upwardly and forwardly over the mortise plate of the fore part section to 15 reduce the over all length of the last sections and to withdraw the heel section of the last from within the heel end of the shoe in an upward and forward direction clearing the heel end of the shoe, said mortise and tenon 20 plates being formed wedgingly to interlock in said normal full last length position of the heel section.

3. A shoe last comprising a fore-part, a separate heel part, a link extending from the 25 fore-part to the heel part, means pivotally connecting one end of the link with one part, an abutment movably carried by the link in proximity to the other end, abutable means embodied in the other part, and yieldable 30 means mounted on the link urging said abutment into contact with said abutable means.

4. A shoe last comprising a fore-part, a separate heel part, a connecting link extending from the fore-part to the heel part said 35 link having a slot in proximity to one end, abutment means movably occupying the slot, yieldable means carried by the link acting on the abutment means to urge it toward one end of the slot, abutable means carried by 40 one of the sections for engagement by the abutment means, and means to pivotally connect the other end of the link with the other section.

5. A shoe last comprising a fore-part, a 45 heel part, a connecting link extending from the fore-part to the heel part, means for pivotally connecting one end of the link to one of said parts to enable a relative sliding and swinging motion of said part in reference to the other part, yieldable means on the other 50 end of the link, and means on said other part along which the yieldable means has sliding and swinging motion.

6. A shoe last comprising a fore-part, a 55 separate heel part, a connector on one of said parts, means on the other part with which the connector is slidably joined, said means including portions of different angularity, and means yieldably connecting the fore-part 60 to the heel part, compensating for the different motions of one part relatively to the other while said connector traverses said portions of different angularity.

7. A shoe last comprising a heel part, a 65 separate fore-part, a link pivoted on the heel

part and reaching into the fore-part, a member fixed on the fore-part through which the link extends, yieldable means carried by the link bearing against and riding upon said member during motions of the heel part 70 relatively to the fore-part, and spaced overhangs projecting from the fore-part between which a portion of the heel part is fitted serving to limit the motions of the heel part in opposite directions.
